US00D553099S

(12) **United States Design Patent** (10) **Patent No.:** **US D553,099 S**
Pape et al. (45) **Date of Patent:** **** Oct. 16, 2007**

(54) **POWER CONTROLLER ASSEMBLY**

(75) Inventors: **Robert A. Pape**, Winona, MN (US);
Larry E. Tiedemann, Winona, MN (US); **Theodore T. Von Arx**, La Crescent, MN (US)

(73) Assignee: **Watlow Electric Manufacturing Company**, St. Louis, MO (US)

(**) Term: **14 Years**

(21) Appl. No.: **29/252,371**

(22) Filed: **Jan. 20, 2006**

(51) **LOC (8) Cl.** **13-03**

(52) **U.S. Cl.** **D13/164**

(58) **Field of Classification Search** **D13/110, D13/119, 123, 133, 147, 152, 154, 159–164, D13/177, 184; D10/94, 46, 125; 361/690, 361/678, 647, 605; D12/192; 312/100; 307/149, 125, 113; 232/4 R, 1 D; 220/324, 220/3.8; D14/239**

(57) **CLAIM**

The ornamental design for a power controller assembly, as shown and described.

DESCRIPTION

The FIGURE is a front view of the power controller assembly, showing our new design.

The broken lines are included for the purpose of illustrating environmental structure and form no part of the claimed design.

1 Claim, 1 Drawing Sheet
